(57) **CLAIM**

The ornamental design for a tripod substantially as shown and described.

DESCRIPTION

FIG. 1 is a top perspective view of a tripod in a stowed configuration in a first embodiment;

FIG. 2 is a top perspective view of the tripod of FIG. 1 with legs in a first position;

FIG. 3 is a top perspective view of the tripod of FIG. 1 with legs in a second position;

FIG. 4 is a front view of the tripod of FIG. 1 in a stowed configuration;

FIG. 5 is a rear view of the tripod of FIG. 1 in a stowed configuration;

FIG. 6 is a left side view of the tripod of FIG. 1 in a stowed configuration;

FIG. 7 is a right side view of the tripod of FIG. 1 in a stowed configuration;

FIG. 8 is a top view of the tripod of FIG. 1 in a stowed configuration;

FIG. 9 is a bottom view of the tripod of FIG. 1 in a stowed configuration;

FIG. 10 is an enlarged view of the encircled area 10 of FIG. 1;

FIG. 11 is an enlarged view of the encircled area 11 of FIG. 4;

FIG. 12 is an enlarged view of the encircled area 12 of FIG. 7;

FIG. 13 is an upper perspective view of a tripod in a second embodiment;

FIG. 14 is an upper perspective view of the tripod of FIG. 13 with legs in a first position;

FIG. 15 is an upper perspective view of the tripod of FIG. 13 with legs in a second position;

FIG. 16 is a front view of the tripod of FIG. 13 in a stowed configuration;

FIG. 17 is a rear view of the tripod of FIG. 13 in a stowed configuration;

FIG. 18 is a left side view of the tripod of FIG. 13 in a stowed configuration;

FIG. 19 is a right side view of the tripod of FIG. 13 in a stowed configuration;

FIG. 20 is a top view of the tripod of FIG. 13 in a stowed configuration; and,

FIG. 21 is a bottom view of the tripod of FIG. 13 in a stowed configuration.

The dash-dash broken lines in the drawings depict portions of the tripod that form no part of the claimed design. The

(Continued)

dash-dot broken lines in the drawings indicate the enlarged views and form no part of the claimed design.
